UNITED STATES PATENT OFFICE

170,531

GAME BOARD

August J. Hennig and William L. Waechter,
Chicago, Ill.

Application April 2, 1953, Serial No. 24,322

Term of patent 14 years

(Cl. D34—5)

To all whom it may concern:

Be it known that we, August J. Hennig and William L. Waechter, have invented a new, original, and ornamental Design for a Game Board, of which the following is a specification, reference being had to the accompanying drawing, forming a part hereof.

The figure is a perspective view of a game board embodying our design.

The game board is of conventional thickness.

We claim:

The ornamental design for a game board, as shown and described.

AUGUST J. HENNIG.
WILLIAM L. WAECHTER.
